UNITED STATES PATENT OFFICE.

EMERY M. HAMILTON, OF NEW YORK, N. Y.

TYPE-WRITING MACHINE.

SPECIFICATION forming part of Letters Patent No. 430,775, dated June 24, 1890.

Application filed February 10, 1890. Serial No. 339,770. (No model.)

To all whom it may concern:

Be it known that I, EMERY M. HAMILTON, of the city, county, and State of New York, a citizen of the United States, have invented 5 certain new and useful Improvements in Type-Writing Machines, of which the following is a full, clear, and exact description, reference being had to the accompanying drawings, forming part of this specification.

My invention relates to what is known as the "spacing-key" of a type-writing machine; and it consists, primarily, in a spacing-key which is pivotally jointed or hinged at each end to its supporting-levers; and my invention 15 further consists in the devices hereinafter described, whereby the pivotal joint is constituted between the spacing-key and its supporting-levers.

Figure 1 is a plan of parts of a type-writing 20 machine and showing a spacing-key containing my invention. Fig. 2 is a vertical cross-section of the machine on the line $x-x$, Fig. 1, in front of the spacing-key and looking toward the rear of the machine; and Fig. 3 is a 25 vertical longitudinal section of the machine on the line $y-y$, Fig. 2.

In the machine shown in the drawings, the type-bars, their key-levers and connections, the key-board, and the paper-carriage are not 30 shown, as they constitute no part of my present invention. A portion of the paper-carriage-actuating mechanism is shown; but the novel features thereof do not need to be described herein, and are reserved herefrom and 35 are fully described in and as part of the subject-matter of a separate application for Letters Patent filed simultaneously herewith, Serial No. 339,767.

In the machine shown, A is the usual lever, 40 which is engaged by all the type-bar key-levers (not shown) to effect the longitudinal step-by-step movement or letter-feed of the paper-carriage through the medium of the vibratory arm a of said lever, a reciprocating bar a' which said arm engages, and the spring-controlled pawls $a^2 a^3$, working to a rack a^4 on the carriage, said rack being connected to a pulling-spring a^5 by a cord a^6 . This lever A is commonly known as the "universal" lever, 45 and in the machine shown has a bar a^7 pivotally hung to the arm a^8 of the said lever,

over which bar the key-levers pass in engagement therewith.

B B' are the spacing-key levers, fulcrumed, as at b , and engaging the universal lever A, 55 as by passing over the bar a' , carried by the arm a^8 of said universal lever.

In carrying out my invention I prefer to provide the levers B B' at their forward ends with the vertical extensions $b' b^2$, respectively, 60 and these extensions may be advantageously pivotally connected to said levers, as at b^3 . I prefer to employ these vertical extensions $b' b^2$ for the reason that in the organization of my type-writing machine I desire to locate my 65 spacing-key at the rear of the key-board and immediately in front of the paper-carriage, and in such construction these extensions $b' b^2$ serve to reach from the spacing-key levers to the spacing-key and connect the same together. The location of the spacing-key may, however, be varied in the machine without departure from the essential features of my invention.

C is the spacing-key, consisting, preferably, 75 of a plate of wood or metal, as shown, and of a length adapted to reach from one to the other of the levers B and B', as shown. The spacing-key C is pivotally jointed or hinged at or near each end to the levers B and B', and 80 preferably to the upper ends of the vertical extensions $b' b^2$ of said levers, as shown. I find it desirable when said vertical extensions $b' b^2$ are employed to constitute these pivotal joints or hinges by means of a socket-piece c , 85 adapted to fit detachably to the upper end of the vertical extension and a plate c' , which is secured to the under face of the spacing-key, as by screws c^2 , said plate being mortised or slotted at c^3 to receive the solid head of the 90 socket-piece c , and a pivot-pin c^4 being passed transversely through the plate and socket-head, as shown. By means of this construction the plates c' , having the socket-pieces c pivoted to them, may be readily secured in 95 proper positions on the key C, and the socket-pieces c may then be conveniently seated on the extremities of the vertical extensions $b' b^2$.

By means of this spacing-key C, pivotally jointed at each end to the supporting-levers 100 B B', the carriage may be moved to effect spacing on the line of printing by depressing

the key in the middle or at either end, and when the key is depressed at one end the lever at such end of the key will act to vibrate the universal lever A, while the other lever 5 remains idle, and the joint of the spacing-key thereto acts as a pivot on which the key oscillates. The operator may thus actuate the spacing-key with either hand, as may be most convenient at the instant when spacing is desired to be effected while printing with the machine, and may effect the spacing with the exertion of only such force on the spacing-key as is necessary to depress but one of the spacing-key levers in engagement with the 15 universal lever.

What I claim as my invention, and desire to secure by Letters Patent, is—

1. In a type-writing machine, a spacing-key pivotally jointed at each end thereof to its 20 supporting spacing-levers, substantially as and for the purpose set forth.

2. In a type-writing machine, the combination, with the spacing-key and its supporting spacing-levers, of vertical extensions on said 25 supporting-levers respectively, and pivotal joints uniting said spacing-key at each end thereof to said vertical extensions, substantially as and for the purpose set forth.

3. In a type-writing machine, the combination, with the spacing-key and its supporting 30

spacing-levers, of vertical extensions on said supporting-levers respectively, and pivotally connected thereto, and pivotal joints uniting said spacing-key at each end thereof to said vertical extensions, substantially as and for 35 the purpose set forth.

4. In a type-writing machine, the combination, with the spacing-key and its supporting spacing-levers, of plates secured to the spacing-key at each end thereof, vertical extensions on said supporting-levers, and socket-pieces fitted on the said vertical extensions, said socket-pieces being pivotally jointed to said plates respectively, substantially as and for the purpose set forth. 45

5. In a type-writing machine, the combination, with the spacing-key and its supporting spacing-levers, of slotted plates secured to the under face of the spacing-key, vertical extensions on said supporting-levers, and socket-pieces detachably fitted on said vertical extensions, with their heads located in the slots in said plates on the key, together with pivot-pins passing through said plates and socket-heads respectively, substantially as and for 50 the purpose set forth. 55

EMERY M. HAMILTON.
